METHOD OF RECOVERING GASOLINE FROM
GASES

Percival C. Keith, Jr., Peapack, and Henry M. Nelly, Jr., Jersey City, N. J., assignors to The M. W. Kellogg Company, Jersey City, N. J., a corporation of Delaware

Application April 23, 1938, Serial No. 203,860

7 Claims. (Cl. 62—175.5)

Our invention relates to a method of recovering gasoline from gases.

Customary absorption systems used for recovering gasoline from gases are not efficient when the gases which are to be subjected to absorption are lean.

One object of our invention is to provide a method of recovering gasoline from lean gases.

Another object of our invention is to provide an economical method of recovering gasoline and other liquid fractions from natural gases containing the same.

Other and further objects of our invention will appear from the following description.

15 The accompanying drawing which forms part of the instant specification and is to be read in conjunction therewith is a schematic view of one form of apparatus capable of carrying out the method of our invention.

20 It has been suggested to use low temperature rectification for the recovery of gasoline from gases. We have found, however, that when this is attempted gas hydrates form, which clog the lines and prevent further operation of the process. In general, our invention contemplates the 25 dehydration of the gas before its reduction in temperature. The dehydration is conducted to such an extent that, at the temperatures involved, gas hydrates will not form.

30 More particularly referring now to the drawing, a feed gas is charged through pipe 1 into a gas scrubber or "knock-out" drum 2. In a typical plant adapted to carry out the method of our invention, we have been able to recover 35 11,800 gallons of gasoline per day, charging 10,000,000 cubic feet of gas per day. The scrubbing liquid may be any desirable liquid such as a slop crude, which is introduced into the scrubbing drum 2 through line 3, removed through

40 line 4, and pumped by pump 5 to slop crude storage. The scrubbed gas leaves the drum 2 through pipe 6 at atmospheric pressure and at a temperature of about 100° F. The gas from pipe 6 passes through pipes 7 and 8 to compressors 9 and 10 in which the gas is compressed to a pressure of about 75 pounds per square inch at which

45 pressure the temperature will be about 270° F. The gas leaves the compressors 9 and 10 through pipes 11 and 12 and passes into pipe 13 into a heat exchanger 14 into which cooling water is introduced through pipe 15. The heat exchanger is such that the gas leaving the heat exchanger 14 through pipe 16 will be at a temperature of about 100° F. This gas enters heat 50 exchanger 17 in which it is reduced in temper-

ature by heat exchange with a chilled gaseous medium. This chilled gas is withdrawn from flash drum 18 through pipe 19 by which it is conducted to heat exchanger 17. The chilled gas is normally at a temperature in the vicinity of —30° F. The rate of flow of the feed gas is such with respect to the rate of flow of the cooling gas that the feed gas leaving the heat exchanger 17 through pipe 20 will be at a temperature of about 41° F. This temperature is sufficient to 10 liquefy considerable water and liquid fractions contained in the gas. The cooled feed gas is introduced from pipe 20 into a water separator tank 21 from which water is withdrawn through pipe 22. At the temperatures involved and for the rate of feed given in a plant operated according to our invention, about 1200 pounds of water per hour were withdrawn from the water separator drum 21. About 200 gallons of gasoline 15 per hour were also precipitated. This gasoline was withdrawn from the separator 21 through pipe 23 and pumped by pump 24 through pipe 25 for introduction into the stabilizer tower 26 via pipes 27 and 28. The cooling gas introduced into the heat exchanger 17 through pipe 19 is withdrawn from the heat exchanger through pipe 27' and introduced into a manifold 28' from which it may be withdrawn through pipes 30 and 31 for use as fuel or discharged as tail gas 20 through pipe 31. If desired, tail gas may be used 25 as a revivifying medium for the driers 32 and 33 as will be hereinafter more fully pointed out.

The cooled gas, freed of precipitated water and gasoline, is removed from the separator 21 through pipe 34 and passed to the drying step. 35 The gas will be substantially at the same temperature in pipe 34 as when it entered the separator, namely at about 40° F. The driers 32 and 33 comprise chambers 35 and 36 adapted to be operated alternately. The gas from pipe 34 40 is introduced into the manifold 37. By opening the valve 38 and closing valve 39, drier 32 will be the one in use. A body of an adsorptive medium 40, such as silica gel, serves to adsorb moisture from the gas. The temperature of the gas entering the drier is above that at which the gas hydrates will form. The drying is such that the gas may now be chilled to a much lower temperature, enabling the recovery of substantial amounts of gasoline from the gases being subjected to our process. The dried gases leave the drier 32 through manifold 41 and pass into pipe 42. When drier 32 is in use, valve 43 will be open and valve 44 will be closed. After drier 32 45 has been in use for a period, it becomes humidi- 50

fied and its dehydrating ability decreases. When this point is reached, valves 38 and 43 are closed and valves 39 and 44 are opened. Valve 45 is opened, permitting tail gases from manifold 28 to pass through heat exchanger 46 in which the gases are heated by superheated steam introduced through pipe 47, to a temperature of about 325° F. Valve 48 is closed and valve 49 is opened. The gases leaving the heat exchanger 46 through pipe 50 may pass through the chamber 35, heating the body of silica gel 40 and evaporating moisture therefrom. The drying gases that contain moisture leave the drier 32 through pipe 51 and valve 52 being open and valve 53 being closed, 15 the gases will pass through pipe 54 to the tail gas manifold 28. The heating of the gases expands them, causing them to flow through pipe 54 into the manifold 28. It will be understood, of course, that the drying gases may be directed 20 to drier 33 by opening valve 48 and closing valve 49 when drier 32 is in use.

The dehydrated gases from pipe 42 pass into a heat exchanger 55 where they are chilled to a very low temperature. The cooling medium for 25 the chilling passes to a heat exchanger 55 through pipe 56 and may comprise liquid propane, withdrawn by pipe 56 from propane flash drum 57. In chilling the gases in heat exchanger 55, some of the propane will be vaporized. The propane 30 vapors leave the heat exchanger 55 through pipe 58 and pass into the propane flash drum 57, whence they are removed through pipe 59 and pass to a compressor 60, whence they are compressed to about 240 pounds per square inch. 35 The propane gas in pipe 59 will be at a temperature of about -40° F. and at a pressure of about 13 pounds per square inch. The propane leaving the compressor 60 through pipe 61 will be at a temperature of about 135° F. The hot 40 compressed propane is passed through a cooler 62 in heat exchange with a cooling medium such as water introduced through pipe 63 in which the propane is cooled to a temperature of about 100° F. The cooled propane leaves the heat exchanger 62 through pipe 64 and passes into a propane receiver 65. The propane is withdrawn from the receiver 65 through pipe 66 and passed to a heat exchanger 67. In the heat exchanger 67, the propane is cooled by heat exchange with 45 unstabilized gasoline, introduced through pipe 68, being withdrawn by pump 69 from flash drum 18. The unstabilized gasoline passing through the heat exchanger 67 is introduced thereto at a temperature of about -30° F. The propane 50 leaves the heat exchanger 67 through pipe 70 at a temperature of about -40° F. and is introduced into the propane flash drum 57.

The gases leaving the heat exchanger 55 will be cooled to a temperature of about -30° F. 60 This low temperature will precipitate gasoline and low boiling hydrocarbons. The condensed liquid and uncondensed gases are withdrawn from the heat exchanger 55 through pipe 71 and are introduced into the flash drum 18. The gaseous 65 hydrocarbons are withdrawn from the flash drum 18 through pipe 19 as heretofore described. The liquid condensate is withdrawn from the flash drum 18 through pipe 72 controlled by valve 73 and pumped by pump 69 through heat exchanger 70 70 67 as pointed out above.

In the example which is being used throughout this specification, the gasoline leaves the heat exchanger 67 through pipe 74 at a temperature of about 90° F. In pipe 74, the gasoline is joined by 75 the gasoline precipitated in the separator 21 and

the unstabilized gasoline passes into heat exchanger 75 through pipe 27. In the heat exchanger, it is heated to a temperature of about 120° F. and at this temperature, it enters the stabilizer 26 through pipe 28. The gasoline is 5 reboiled in stabilizer tower 26 in reboiler 76 which is supplied steam through pipe 77. The bottom of the tower is kept at a temperature of about 222° F. and is operated under a pressure of 10 140 pounds per square inch. The vapors leaving the top of the stabilizer through pipe 78 are at a temperature of about 125° F. They pass through a heat exchanger 79, supplied with a cooling medium through pipe 80 and are cooled therein to a temperature of about 100° F. The 15 condensate passes from heat exchanger 79 through pipe 81 into a reflux drum 82 from which reflux is withdrawn through pipe 83 and pumped by pump 84 through pipe 85 to the tower as a control reflux, keeping the top tower at about 100° 20 F. Stabilizer gas is vented through pressure control valve 86 by pipe 87. The stabilizer gas may be passed to the tail gas manifold 28. The stabilized gasoline is withdrawn from the stabilizer tower 26 through pipe 88 and passes through heat 25 exchanger 75, being withdrawn therefrom through pipe 89 and passing to storage tanks 90 and 91 whence it is withdrawn through manifold 92. The stabilized gasoline leaving the heat exchanger 75 will be at a temperature of about 30 100° F.

It is to be understood that the temperatures and pressures used throughout this specification are by way of illustration only and not by way of limitation.

35

It will be seen that we have accomplished the objects of our invention. We have provided a method of recovering gasoline from lean gases by low temperature rectification and stabilization while avoiding the formation of gas 40 hydrates. The use of lean tail gas to revivify the driers and the drying of the precooled tail gas before final chilling to prevent the formation of gas hydrates are novel features, enabling the employment of our invention 45 to recover valuable low boiling liquid hydrocarbons suitable for use as a motor fuel from lean hydrocarbon gases. The recovery of the valuable liquid hydrocarbons by means of our method could not be accomplished by conventional absorption or rectification methods.

It will be understood that certain features and subcombinations are of utility and may be employed without reference to other features and sub-combinations. This is contemplated by and 55 is within the scope of our claims. It is further obvious that various changes may be made in details within the scope of our claims without departing from the spirit of our invention. It is, therefore, to be understood that our invention is 60 not to be limited to the specific details shown and described.

Having thus described our invention, we claim:

1. A method of recovering gasoline from mixtures of hydrocarbon gases which comprises 65 compressing hydrocarbon gases, cooling the compressed gases to a relatively low temperature above the freezing point of water and above that at which solid hydrocarbon hydrates will form to condense water and some gasoline, separating the 70 water from the remaining gases and separating the gasoline from the remaining gases, passing the remaining gases through a dryer zone to remove substantially all the moisture from such gases, then reducing the temperature of the re- 75

maining dried gases to a relatively low temperature below the freezing point of water to condense gasoline, combining the gasoline separated in the two cooling steps and introducing it into a stabilizing zone for stabilizing the gasoline.

2. A method of recovering gasoline from mixtures of hydrocarbon gases which comprises compressing hydrocarbon gases, cooling the compressed gases to a relatively low temperature above the freezing point of water and above that at which solid hydrocarbon hydrates will form to condense water and some gasoline, separating the water from the remaining gases and separating the gasoline from the remaining gases, passing the remaining gases through an adsorbing agent in a dryer zone to remove substantially all the moisture from such gases, then reducing the temperature of the remaining dried gases to a relatively low temperature below the freezing point of water to condense gasoline, passing the cooled gases and gasoline to a separating zone to separate gasoline from cold gases and using the separated cold gases for initially cooling the compressed gas at the beginning of the method and thereafter heating the separated gases and using the heated gases as a drying medium for revivifying the adsorbing agent in another dryer zone.

3. A method of recovering liquid hydrocarbons within the gasoline boiling range from mixtures of hydrocarbon gases containing gasoline constituents which comprises cooling said hydrocarbon gases under superatmospheric pressure to a relatively low temperature above the freezing point of water and above that at which solid hydrocarbon hydrates will form to condense water and some gasoline, separating water, liquid hydrocarbons containing gasoline constituents and remaining gases from each other, passing gases thus separated through a dryer zone at a temperature above that at which solid hydrocarbon hydrates will form to remove substantially all of the moisture from such gases, reducing the temperature of the thus dried gases to a relatively low temperature below the freezing point of water to condense liquid hydrocarbons containing gasoline constituents and stabilizing gasoline separated in the two cooling steps.

4. A method of recovering liquid hydrocarbons within the gasoline boiling range from mixtures of hydrocarbon gases containing gasoline constituents which comprises cooling said hydrocarbon gases under superatmospheric pressure to a relatively low temperature above the freezing point of water and above that at which solid hydrocarbon hydrates will form to condense water and some gasoline, separating water, liquid hydrocarbons containing gasoline constituents and remaining gases from each other, passing gases thus separated through a dryer zone at a temperature above that at which solid hydrocarbon hydrates will form to remove substantially all of the moisture from such gases, reducing the temperature of the thus dried gases to a relatively low temperature below the freezing point of water to condense liquid hydrocarbons containing gasoline constituents separated in the two cooling steps and introducing combined constituents into an

enlarged zone wherein volatile constituents are removed.

5. A method of recovering liquid hydrocarbons within the gasoline boiling range from mixtures of hydrocarbon gases containing gasoline constituents which comprises cooling said hydrocarbon gases under superatmospheric pressure to a relatively low temperature above the freezing point of water and above that at which solid hydrocarbon hydrates will form to condense water and some gasoline, separating water, liquid hydrocarbons containing gasoline constituents and remaining gases from each other, passing gases thus separated through a dryer zone at a temperature above that at which solid hydrocarbon hydrates will form to remove substantially all of the moisture from such gases, reducing the temperature of the thus dried gases to a relatively low temperature below the freezing point of water to condense liquid hydrocarbons containing gasoline constituents, separating liquid hydrocarbons containing gasoline constituents from cold gases and utilizing separated cold gases thus obtained for initially cooling the hydrocarbon gases under superatmospheric pressure. 25

6. A method of recovering liquid hydrocarbons within the gasoline boiling range from mixtures of hydrocarbon gases containing gasoline constituents which comprises cooling said hydrocarbon gases under superatmospheric pressure to a relatively low temperature above the freezing point of water and above that at which solid hydrocarbon hydrates will form to condense water and some gasoline, separating water, liquid hydrocarbons containing gasoline constituents and remaining gases from each other, passing gases thus separated through a dryer zone at a temperature above that at which solid hydrocarbon hydrates will form to remove substantially all of the moisture from such gases, reducing the temperature of the thus dried gases to a relatively low temperature below the freezing point of water to condense liquid hydrocarbons containing gasoline constituents, separating liquid hydrocarbons containing gasoline constituents from cold gases, 45 heating cold gases thus obtained and using the heated gases as a drying medium for revivifying the adsorbing agent in another dryer zone. 40

7. A method of recovering gasoline from mixtures of hydrocarbon gases which comprises cooling hydrocarbon gases under superatmospheric pressure to a relatively low temperature above the freezing point of water and above that at which solid hydrocarbon hydrates will form to condense water and some gasoline, separating the water from the remaining gases and separating the gasoline from the remaining gases, passing the remaining gases through a dryer zone at a temperature above that at which solid hydrocarbon hydrates will form to remove substantially all of the moisture from such gases, then reducing the temperature of the remaining dried gases to a relatively low temperature below the freezing point of water to condense gasoline, combining the gasoline separated in the two cooling steps and introducing it into a stabilizing zone for stabilizing the gasoline. 55 60 65
